CLAIM

The ornamental design for a physical workout device, as shown and described.

DESCRIPTION

FIG. 1 is a top view of the principal portion of the invented physical workout device showing the new design;

FIG. 2 is a left end view thereof;

FIG. 3 is a front elevational view thereof;

FIG. 4 is a right end view thereof;

FIG. 5 is a bottom view thereof, and

FIG. 6 is a rear elevational view thereof.

FIG. 7 is a top plan view of an alternative embodiment of the principal portion of the physical workout device of FIG. 1, having no central frontal pad;

FIG. 8 is a left end view thereof;

FIG. 9 is a front elevational view thereof;

FIG. 10 is a right end view thereof;

FIG. 11 is a bottom view thereof, and

FIG. 12 is a rear elevational view thereof.

FIG. 13 is a front view of the principal portion of the physical workout device being utilized on a user's back.

FIG. 14 is a front view of the principal portion of the physical workout device being utilized by a user standing on the device.

FIG. 15 is a perspective view of the complete physical workout device comprising the principal portion and the bar attachment being utilized by an unclaimed user; and,

FIG. 16 is a front view of the complete physical workout device comprising the principal portion and the bar attachment, mounted on an unclaimed pedestal.

Material shown in dotted lines shows the environment in which the invented design is used, and forms no part of the invented design.
